APPARATUS FOR REGISTERING AND SOLDERING DOUBLE PAGE ELECTROTYPE

Harry W. Faeber, Larchmont, N. Y., assignor to Time, Incorporated, New York, N. Y., a corporation of New York

Original application January 31, 1951, Serial No. 208,783, now Patent No. 2,706,946, dated April 26, 1955. Divided and this application August 29, 1952, Serial No. 307,058

2 Claims. (Cl. 113—99)

The present invention relates to apparatus for registering and soldering double page electrotypes and embodies, more specifically, an improved method and apparatus by means of which electrotypes that are to be used in a printing operation to print a double page spread, may be accurately registered and secured together to form a unitary printing surface. The method contemplates providing steps by means of which the securing operation may be effected in such fashion as to avoid interfering with the printed image formed by the double page printing surface and also, as above suggested, provides means by which the two separately formed single page electrotypes may be effectively registered prior to and during the operation in which they are secured together as a unitary structure.

It is common, in many commercial printing operations, to print subject matter upon the facing pages of two adjacent pages of the printed matter. In such an operation it is important, of course, that the subject matter of one adjacent page agree with and provide the desired continuity of the subject matter of the adjacent facing page. It is required in existing operations, that the separate electrotypes of the two adjacent facing pages be soldered together to form a unified double page plate. In multicolor printing, great difficulty is experienced in registering the several color plates of such double page spreads on the press, because the soldering operation does not join the two electrotypes together accurately enough to bring the adjoining images in exactly the same relationship with one another on the several color plates of the same subject. Furthermore, in present practice, any discrepancy of register can only be determined after the plates have been put on the press and a trial impression has been run. Thus it is often required to remove one or more of the color plates from the press, cut them apart and resolder them in an effort to correct the relationship of the adjoining images.

In accordance with the present invention, an apparatus is provided whereby the single page electrotypes composing double page spreads may be accurately registered and secured together in exactly the same relationship on all the several color plates of the same subject well in advance of going to press.

In order that the invention may be more fully understood, it will now be described in connection with the accompanying drawings wherein

Figure 1 is an axonometric view showing certain apparatus that may be used in performing the initial steps of the present invention;

Figure 2 is an axonometric view illustrating the manner in which the single electrotypes shown in Figure 1 are punched to facilitate register of the electrotypes during the operation in which they are secured together;

Figure 3 is an axonometric view illustrating the apparatus by means of which the electrotypes may be secured in position during the soldering or other operation in which the electrotypes are secured together; and

2

Figure 4 is a view in cross-section, taken at line 4—4 of Figure 1.

Referring to the above drawings, the base 10 of a registering mechanism is provided with a hinged plate 11 upon which is carried a transparent and cross-ruled register screen 12. Mating locating lugs 13 and 14 are carried on the members 10 and 11 and, on the base 10, locating wedges 15 are provided. A register block 16 is provided with a plurality of adjusting knobs 17 which operate threaded shafts in the block 16 to adjust the positions of positioning lugs 18. As illustrated in Fig. 1, the lugs 18 are used to position two separate single page electrotypes 19 and 20.

After the electrotypes 19 and 20 have been properly located upon the base 16, as described in greater detail hereinafter, the base is transferred to a punch mechanism comprising a punch table 21 having a plurality of punch fixtures 22, 23, 24, and 25. In the mechanism illustrated, the punch fixture 25 is slidably mounted in tracks 25a upon the table 21. Stop 25b, which is fastened to table 21, locates punch fixture 25 in working position. Table 21 is provided with a plurality of locating wedges 26 similar to the wedges 15 on base 10 by means of which the register blocks 16 may be properly located upon the table 21. Each of the punch fixtures is provided with an operating handle, as illustrated at 27, and the punching operation performed upon the plates will be readily apparent from Figure 2 and will be described in detail presently.

After the punching has been accomplished, the electrotypes 19 and 20 are transferred to a soldering block 28 having spaced pedestals 29 and 30 and adjustable positioning lugs 31. The electrotypes 19 and 20 are secured in position by the lugs 31. Hold down pads 32 and 33 are mounted upon the respective pedestals 29 and 30 by means of piston rods 34 and 35, respectively, actuated by the fluid pressure within the respective cylinders 36 and 37. While the electrotypes are held in the manner illustrated in Figure 3, they are secured together by a soldering operation in a manner presently to be described.

The method of the present invention is performed in the following manner. Two separate single page electrotypes 19 and 20 of the desired double page spread are placed upon the register block 16 as illustrated in Figure 1. Prior to this location of the electrotypes, the joining edges were preferably previously trimmed a trifle inside of the desired joining edges, so as to allow a slight space between the two electrotypes when they are positioned in the proper relationship to one another.

The register screen 12 is then lowered upon the electrotypes and the images of the electrotypes are squared with respect to the screen by means of the knobs 17 and lugs 18.

After the single page electrotypes have been properly located, the register screen is lifted and the electrotypes are inked. A transparency 38 is then placed over the electrotypes and the image thereof printed upon the transparency. During this operation transparency 38, which is clamped between bars 38a at both ends, is stretched tight between bars 16a and 16b. The bars 16a is fastened fixedly to register block 16, but bar 16b can be moved parallel with itself by means of tightening screws 16c and is thus used to stretch the transparency securely over the electrotypes.

The printed transparency is now set aside, and the register block 16 is then transferred to the punch table 21 and properly located by the wedges 26. Punches 22 and 23 are actuated to punch match-up holes 39 and 40 in the electrotypes and register holes 41 and 42 are punched by the respective punches 24 and 25. The register hole 42 is preferably round while the hole 41 is elongated,

and it will be observed that the match-up holes 39 and 40 are half and half in the two joining edges of the electro-types.

The punched electro-types shown in Figure 2 are then placed face down upon the soldering block 28, as illustrated in Figure 3, and flush copper plugs 43 and 44 are placed in the respective match-up holes 39 and 40. The lugs 31 are then moved toward each other until the electro-types are brought up against the plugs 43. The hold down pads 32 and 33 are then lowered to hold the electro-types in the aforementioned position and the adjacent or joining edges, together with the match-up plugs, are soldered together. The joining edges so soldered are indicated at 45 in Figure 3.

The double page spread is then subjected to further finishing operations in accordance with standard practice now commonly used. In this connection, it is to be observed that the register holes 41 and 42 and the match-up holes 39 and 40 are all outside the actual printing area. Thus, in the course of subsequent plate making operations, the holes 41 and 42 and plugs 43 and 44 will be trimmed off.

If the printing operation to be performed is a multi-color one, the previously described registering and soldering operations were preferably performed upon the key electro-types. Having completed the joining of the key electro-types, the successive color electro-types are joined by locating the color electro-types upon the register block 16 and registering them to agree with the printed image upon the transparency 38 (the joining edges having previously preferably been trimmed). After properly registering the color electro-types, the successive punching, soldering and finishing operations are performed as previously described.

Each successive pair of color electro-types are registered, punched and soldered until the entire set is completed.

From the foregoing description it will be apparent that a simple and effective apparatus for registering and soldering sets of single page electro-types has been provided. The invention assures that the respective electro-types are secured in proper registered position and maintained in such position during all subsequent operations.

This application is a divisional application of my co-pending applicaton Serial No. 208,783, filed January 31,

1951, now U. S. Patent No. 2,706,946, dated April 26, 1955.

While the invention has been described with specific reference to the accompanying drawings, it is not to be limited save as defined in the appended claims.

I claim:

1. Apparatus for positioning electro-types during soldering or like securing operations comprising a block forming a supporting surface, two opposed, spaced apart pairs of lugs mounted on said block for movement toward and away from each other to engage the outer ends of a pair of electro-types on said supporting surface, screw means on said block engaging said lugs for adjusting each lug individually to adjust the position of each electro-type on said surface to bring them into a predetermined relation to each other, spaced pedestals fixed to said block outwardly of said pairs of lugs, hold-down pads mounted on said pedestals and movable toward and away from said surface, means on said pedestals for moving said pads toward 15 said surface to engage substantially the mid-portions of said electro-types and clamp them in their adjusted positions for soldering and like operations.

2. The apparatus set forth in claim 1 in which each of said means for moving said pads comprises a cylinder 20 and a piston movable in said cylinder by fluid pressure.
